APPARATUS FOR AUTOMATICALLY STOPPING DIE CASTING MACHINES IN THE EVENT OF SHOT FAILURE

Louis H. Morin, Bronx, N. Y.

Application July 19, 1951, Serial No. 237,611

5 Claims. (Cl. 22—70)

This invention relates to die-casting machines. More particularly, the invention deals with an apparatus for automatically stopping the operation of the machine in the event that the shot stroke of the gooseneck of the machine should fail to function for any reason, so as to render the machine inoperative until such time as the fault is corrected. Still more particularly, the invention deals with a mechanism of the character described, which is directly tied in with the automatically actuated valve controlling supply of compressed air to the plunger controlling discharge of molten metal from the gooseneck.

The novel features of the invention will be best understood from the following description, when taken together with the accompanying drawing, in which certain embodiments of the invention are disclosed and, in which, the separate parts are designated by suitable reference characters.

The drawing is a diagrammatic sectional view through the gooseneck and operating mechanism therefor, showing the valve which controls the operation of said mechanism and illustrating my improved automatic stop.

In die-casting machines and, particularly, machines of this class which operate automatically at high speeds, it is customary to provide one attendant to a large number of machines. At times, it has been experienced that a nozzle or other clogging takes place, which clogging might comprise a freezing of metal at the discharge of the nozzle. On the other hand, a gate may clog the nozzle hole controlling admission to a die cavity.

In automatic machines of the kind under consideration, the development of such a clogging condition would result in the machine continuing to operate for a period of time, until this fault would be noted by an operator and this improper functioning of the machine, if nothing else, would result in a production loss and the failure to produce die castings in each cycle of operation of the machine.

The object of my present invention deals with the provision of an automatic stop mechanism which will instantaneously stop the operation of the machine at the moment that the discharge plunger, for discharging molten metal from the nozzle of the machine, fails to perform its normal function and this automatic stop mechanism is tied in with the air control valve in a simple manner, so as to utilize the same air for actuation of a stop switch which will break the motor circuit, causing the machine to stop immediately, particularly, in utilizing a brake-type of motor for actuating the casting machine.

In the accompanying drawing, I have diagrammatically shown such parts of a die casting machine, as will illustrate the function and operation of my improved automatic stop mechanism.

5. In the drawing, 10 represents a conventional pot containing the molten metal 11, the pot having suitable means for heating the same, as indicated at 12, to maintain the metal 11 at the proper temperature. Supported in and above the pot 10 is a gooseneck mechanism 13, comprising a lower discharge cylinder 14, in which the discharge plunger 15 operates, the cylinder 14 having the upwardly and outwardly extending discharge arm 16 having, at its end, the conventional discharge nozzle 17, through which the heated metal is adapted to be pressure discharged into the cavity of suitable dies, the latter being omitted.

Above the cylinder 14 is a cylinder 18, which 20 joins the cylinder 14, in a series of ribs 19. The plunger 15 extends into the cylinder 18 and has thereon a piston 20 with an O-ring or other seal 21 in the cylinder 18.

The lower end of the cylinder 18 has a seat 22 25 for a coil spring 23, which bears against the piston 20 to normally support the same and the plunger 15 in raised position. Air is exhausted from the cylinder 18 through clearance, as at 24, between the seat 22 and plunger 15. The 30 plunger 15 includes an extension 25, above the piston 20 and operating in a suitable bearing block 26, the extension 25 extending above the block and having an adjustable collar 27 thereon, the collar having a radial arm 28, in which is supported an adjustable screw 29.

The screw 29 operates upon a spring backed pin 30 operating in a by-pass control tapered valve 31, which controls by-passing of compressed air from port 32 to pipe 33 extending to a suitably 35 supported small cylinder 34, in which is mounted a piston actuated pin 35. The pin 35 is normally set by a spring 36 and, when actuated by air against the action of the spring 36, said pin will operate a button 37 of a micro-switch 38. The 40 switch 38 controls the circuit to the electric motor 39, which is of a brake-type and is diagrammatically shown in the accompanying drawing. The motor 39 controls the operation of the casting machine. Thus, it will be apparent that, when 45 the micro-switch 38 is actuated, the machine will be instantaneously stopped.

At one side of the cylinder 18 is a tubular valve casing 40, in which is slidably mounted a control valve 41. The valve 41 carries, at its outer forked end 42, a roller 43 held in constant engagement with an operating cam 44 by a coil spring 45. It

will be understood that the shaft 46 of the cam is automatically actuated from the motor 39 through a suitable drive, which is not shown.

As will appear, the roller 43 operates in an open end portion 47 of the casing 40 and, in the position shown, the valve 41 has been actuated by the cam 44, so as to place the port 48 of the valve in communication with the source of compressed air supply as through pipe 49 with the pipe 50 which leads to the admission port 51 of the cylinder 18 and, accordingly, the piston 20 will, in such position, be moved downwardly to actuate the discharge plunger. In the drawing, it is shown in the raised position. It will be understood, however, that, as air enters the cylinder 18, the piston 20 will be moved downwardly for actuation of the plunger 15.

The pipe 50 contains a T-coupling 52 that has a branch 53 connected to the valve casing 40. When the rise or bump 54 on the cam 44 moves the valve 41 further into the casing 40, a port 55 in the valve is positioned so as to place the branch 53 in communication with pipe 56. Air will thus be admitted to the port 32 in a direction to raise or open the by-pass valve 31. However, under normal conditions; i. e., when the piston 20 and plunger 15 have moved downwardly for their full stroke, the screw 29 carried by the extension 27 of the plunger engages with the pin 30 and holds the valve 31 seated or closed, thus preventing air from entering the pipe 33 from the port 32 and, consequently, the micro-switch 38 will not be operated.

The foregoing statement is based on the normal successful operation of the plunger 15 in pressure discharging metal from the gooseneck 14 or nozzle 17 into a die cavity. However, should the plunger 15 be checked or held against its full downward movement by a clogged condition prevailing anywhere in the line of flow of metal to the die cavity, then the checked downward movement of the plunger 15 will prevent the valve 31 from being held in its seated or closed position and air will be permitted to pass into the pipe 33 from the port 32 to actuate the pin 35, button 37 and micro-switch 38, thus instantaneously stopping the motor 39.

The inner end of the valve 41 has an exhaust passage 57 which is adapted to register with the pipe 56 when the cam 44 is in its low position, so as to exhaust air from the pipes 33, 56 through the exhaust port 58 in the casing 40. The casing 40 has another exhaust port 59, at its outer end, with which the port 48 communicates for exhausting air from the cylinder 18 and pipe 50 in the same position of the valve 41, mentioned above. For this purpose, the end of the port 48 communicating with the pipe 50 is elongated so that it remains in communication with the pipe 50 in the latter position of the valve 41, but the supply of compressed air from the pipe 49 is shut-off by the movement of the valve 41.

By providing the adjustable screw 29 for actuating the pin 39, a definite setting can be made to control the seating of the valve 31 in the operation of the machine. From the foregoing, it will be apparent that, in each cycle of operation of the cam, the valve 41 will complete its inward and outward stroke motion and, in normal operations of the machine and when a casting charge or shot has been successfully discharged from the nozzle 17, the machine will continue to function, the valve 31 being, at all times, held in its seated position when air is admitted thereto. However, if a full charge or shot of casting material has not

taken place, the valve 31 will be free to be opened and the micro-switch will be actuated instantaneously to stop operation of the machine. At least, this operation will be performed before another cycle of operation of the machine takes place.

Having fully described my invention, what I claim as new and desire to secure by Letters Patent is:

1. In a die casting machine of the character described which employs a gooseneck and a plunger operating in the gooseneck for discharging molten metal under pressure into a die cavity, the combination of pneumatically operable means for controlling the operation of the machine, a valve connected to a supply of air under pressure, said valve in one position connecting the supply of air to the plunger in the gooseneck and in second position connecting the supply of air to said pneumatically operable means, a second valve connecting the pneumatically operable means to the supply of air through said first-mentioned valve and means controlled by movement of the plunger for holding said second-mentioned valve closed at one position of the plunger.
2. In a device for automatically controlling the operation of a die casting machine of the type employing a gooseneck with a plunger operating therein for discharging molten metal under pressure into a die cavity, the combination of pneumatically operable means for controlling operation of the machine, a slide valve comprising a casing and a valve body slidably mounted in said casing, said casing having a port communicating with a supply of air under pressure and ports communicating with the plunger and the pneumatically operable means, said valve body having a passageway therein connecting the port communicating with the supply of air to the port communicating with the plunger at one position of the body and a second passageway connecting the supply of air under pressure to the pneumatically operable device at a second position of the body, valve means connecting the pneumatically operable device to said slide valve and means on said plunger for controlling operation of said last-mentioned valve means.
3. In a die casting machine which employs a gooseneck with a plunger operating therein for discharging molten metal under pressure into a die cavity, the combination of a motor controlling operation of the machine, a switch controlling operation of the motor, pneumatic means for operating said switch, means comprising a slide valve for controlling air operation of the plunger and said pneumatic means and means operable by said plunger for rendering said pneumatic means inoperable at one position of the plunger.
4. In an automatically actuated die casting machine employing a gooseneck with an air operated plunger therein for discharging molten metal from the gooseneck into a die cavity and a motor controlling operation of the machine, the combination of an air actuated switch for controlling operation of the machine, a slide valve connected to a supply of air under pressure, said valve connecting the supply of air to the plunger at one position of the valve and to the air actuated switch at a second position of the valve, means connected to the motor for moving said valve to said position, a check valve communicating with the air actuated switch and the supply of air under pressure and means on said plunger engaging with and holding said check valve closed at one position of the plunger.

5. In a die casting machine of the type employing a gooseneck with a plunger operating in the gooseneck for pressure discharge of molten metal in the formation of die castings and having an electric motor for controlling the operation of the machine, an apparatus for automatically stopping machine operation upon failure of the plunger to complete a normal injection stroke, said apparatus comprising a switch in circuit with said electric motor, an air actuated device for operating said switch, a valve connecting a supply of air under pressure to said plunger at one position of the valve and to the air actuated device at a second position of the valve, a check valve connecting the air actuated device to the supply of air under pressure through said first-mentioned valve, said check valve hav-

ing an operating member and adjustable means on the plunger positioned for engagement with said operating member, said last-mentioned means engaging with and holding the check valve in closed position upon completion of a full stroke of the plunger.
